UNITED STATES PATENT OFFICE

HARRY PACK, OF JOHNSON COUNTY, KANSAS

DESIGN FOR A PORTABLE DISPLAY RACK

Application filed August 3, 1931. Serial No. 40,768. Term of patent 3½ years.

To all whom it may concern:

Be it known that I, HARRY PACK, a citizen of the United States, residing in Johnson County, Kansas, have invented a new, original, and ornamental Design for a Portable Display Rack, of which the following is a specification, reference being had to the accompanying drawings, forming part thereof, in which—

Fig. 1 is a perspective view of a portable display rack, showing my new design.

Fig. 2 is a perspective view of the portable display rack turned at approximately right angles to the position disclosed by Fig. 1.

Fig. 3 is a perspective view of the portable display rack turned approximately half way around from the position shown by Fig. 1.

I claim:

The ornamental design for a portable display rack, as shown.

HARRY PACK.
